UNITED STATES PATENT OFFICE

ARTHUR D. PRATT, OF SHORT HILLS, NEW JERSEY, ASSIGNOR TO THE BABCOCK & WILCOX COMPANY, OF BAYONNE, NEW JERSEY, A CORPORATION OF NEW JERSEY

STEAM BOILER

Application filed May 10, 1928. Serial No. 276,554.

My invention more particularly relates to a steam boiler comprising a reheater which is advantageously arranged in the boiler and cooperates with the other parts thereof.

5 My invention will best be understood by reference to the accompanying drawings, in which I have illustrated a preferred embodiment of my invention, and in which Fig. 1 is a vertical section through a steam boiler embodying my invention, and Fig. 2 is a sectional plan view, the left-hand portion being taken on the line 2—2 of Fig. 1, and the right-hand portion thereof taken on the line 2^a—2^a of Fig. 1.

15 Like reference characters indicate like parts throughout the drawings.

Referring now to the drawings, 10 and 11 are upper steam and water drums, and 12 is a lower mud drum connected to the upper steam and water drum 10 by a bank of tubes 13, and to the upper steam and water drum 11 by two banks or groups of tubes 14 which are preferably located at the respective sides of the boiler as best shown in Fig. 2. One 20 of the side walls of the setting is indicated in Fig. 2 at 141, the wall being provided with an inwardly extending portion as at 142 to form a contracted portion at 143, this portion extending forwardly as at 144 to a bridge wall 18. The groups of tubes 14 are preferably located outside of the plane of the inner surface of the contracted portion 143 of the setting. The tubes 14 are preferably arranged in rows at right angles to the axis of 25 the drum, and the lower portions of the outer three rows of tubes, as shown in Fig. 2, are located in a recess 145 formed between the outermost wall 141 of the setting and the projection 144. Locating at least a portion of 30 some of the tubes in this recess in the described manner, promotes circulation in the tubes.

Tubes 15, arranged in a row parallel to the axis of the drum, are preferably provided having straight portions lying in a plane immediately in front of and parallel to the tubes 14, but bent at their upper ends and entering the front steam and water drum 10.

35 The upper steam and water drums 10 and

11 are connected by usual water circulators 16 and steam circulators 17.

A bridge wall 18 is located at the rear of the mud drum 12, and is supported on an I-beam 19. A baffle 20 extends upwardly from the mud drum 12 at the rear of the front bank of tubes 13, and stops short of the steam and water drum 10. A second baffle 21 extends downwardly from the rear steam and water drum 11 between the tubes 14 and the single row of tubes 15, the latter baffle stopping short of the lower drum 12.

In the embodiment of my invention illustrated, a superheater illustrated generally at 220, comprises looped tubes 221 connected at one end to an inlet header 222 in turn connected to the steam and water drum by a pipe 53, the other ends of the tubes 221 being connected to an outlet header 224.

40 In accordance with my invention, a reheater for heating the steam from the intermediate stages of a steam turbine or other steam engine is employed. Such a reheater is indicated generally at 22, and comprises three headers, 23, 24, and 25, in the embodiment 45 illustrated, located one above the other, the headers 23 and 24 being connected by U-tubes 26 located in a flue 27 behind the bridge wall 18 and beside the flue defined between the wall 18 and the baffle 21, the tubes extending 50 back and forth across said flue. The headers 24 and 25 are connected by U-tubes 28, which preferably extend over and are supported by the bridge wall 18. The ends of the U-tubes 28 are preferably supported by 55 plates 28' which extend upwardly from the bridge wall 18, the ends of the tubes being arranged in overlapping arrangement with the boiler tubes 14, thereby providing a compact structure which occupies the minimum 60 amount of floor space.

A removable door 29 is preferably provided between the headers 24 and 25 through which the U-tubes 28 may be removed, and a removable door 30 is provided between the headers 23 and 24 through which the U-tubes 26 may be removed. The doors and headers form a baffle or wall defining the rear portion of the flue 27, this baffle or wall being completed 65 by a plate 31 extending upwardly from the 70

header 25 to the roof 32, and a baffle member 33 extending downwardly from the header 23, the lower portion of the member 33 preferably being inclined rearwardly as illustrated.

5 A vertical flue 271 communicates with the lower portion of the flue 27, and in the flue 271 is located an economizer indicated generally at 34 and comprising U-tubes 34' extending across the flue and connected to inlet and outlet headers 35 and 36, respectively. In the flue 271 above the economizer 34 is preferably located an air heater indicated generally at 37 and comprising tubes 38 connected 10 at their upper and lower ends, respectively, to tube sheets 39 and 40 extending transversely across the flue. The gases flow upwardly through the tubes 38, and air preferably flows in a generally downward direction over the tubes, entering the space surrounding the tubes through an inlet 41, and leaving by an air outlet 42, the gases preferably being directed over the tubes by angled baffles 43, as shown in Fig. 1. The air heater is preferably supported by I-beams 44.

15 The U-tubes 26 and 28 of the re heater are preferably supported by rods 45 extending transversely across both banks of tubes, the upper ends of the rods preferably being supported by links 46 from I-beams or other fixed members 47 of the setting.

20 A soot pocket 48, which may be supported by I-beams 49 and 50, is preferably located beneath the flue 271 and is arranged to catch the soot and dust carried by the gases and which are thrown out of the gases where they make the turn from the flue 27 to the flue 271. A soot conveyor 51 is preferably provided in the lower portion of the soot pocket 48 for the removal of soot and other solid matter.

25 The feed inlet is indicated at 52 in the rear steam and water drum 11, and the steam outlet at 53 leading to a superheater indicated generally at 220. A portion of the furnace chamber is indicated at 54 above a furnace not illustrated.

30 The operation of the boiler embodying my invention will readily be understood from the foregoing description and is as follows:

35 The heated gases from the furnace chamber 54 flow upwardly over the tubes of the front bank 13 and over the upper end of the baffle 20, and then flow downwardly over the single row of tubes 15, and over the superheater tubes 221, and underneath the baffle 21, then flow upwardly through the flue defined by the baffle 21 and the bridge wall 18 over the tubes 14 and over the front bent ends 60 of the tubes 28. The gases then flow downwardly over the tubes of the re heater indicated generally at 22, around the lower end of the baffle 33 into the flue 271 and thence upwardly over the tubes of the economizer 65 and through the tubes of the air heater to

the stack. Steam preferably enters the header 23 and flows upwardly through the tubes 26 to the header 24, and then through the tubes 28 to the outlet header 25, the steam in the re heater thus flowing in a direction generally counter to the flow of the gases thereover.

70 It will be seen that with the arrangement described, a comparatively small amount of boiler heating surface is interposed in the path of the furnace gases between the furnace and the tubes of the re heater. Furthermore, by arranging some of the tubes of the re heater in overlapping arrangement with the tubes 14 of the boiler as viewed longitudinally of the drums, the space for the boiler is better utilized. The re heater is included in a space between the levels of the upper and lower drums, so that no additional height is required in the steam boiler, and since the tubes overlap with the boiler tubes, the minimum of floor space is required, and the width is less than the combined width of the two. The invention is particularly applicable to a boiler having vertically extending tubes, and especially a boiler of the general Stirling type in which no headers, such as commonly used with horizontally extending water tubes, are used.

75 It will be obvious that by varying the relative number of boiler tubes and re heater tubes, any desired relative amount of steam generated and reheating of the steam may be obtained.

80 I claim:

1. In combination, a steam boiler and its setting comprising two side by side flues, the gases flowing upwardly in a first flue, and downwardly in a second flue, vertically extending boiler tubes located in said first flue, and re heater tubes having portions overlapping with said boiler tubes in said first flue and having other portions extending across said second flue.

85 2. In combination, a steam boiler and its setting comprising two side by side flues, boiler tubes located in one of said flues, and re heater tubes having one portion of the tubes located in the last-mentioned flue in overlapping arrangement with the boiler tubes, said re heater tubes being provided with other portions extending across said second flue.

90 3. In combination, a steam boiler and its setting comprising two side by side vertically extending flues, boiler tubes located in one of said flues, and re heater tubes having one portion of the tubes located in the last-mentioned flue in overlapping arrangement with the boiler tubes, said re heater tubes being provided with other portions extending across said second flue below said first-mentioned re heater tubes.

95 4. In combination, a steam boiler and its setting comprising two side by side flues,

- boiler tubes located in one of said flues, and reheater tubes having one portion of the tubes located in the last-mentioned flue in overlapping arrangement with the boiler tubes, said reheater tubes being provided with other portions extending across said second flue, the steam flowing through said reheater tubes in a direction generally counter to the flow of the gases.
5. In combination, a steam boiler and its setting comprising two side by side flues, boiler tubes located in one of said flues, and reheater tubes having one portion of the tubes located in the last-mentioned flue in overlapping arrangement with the boiler tubes, said reheater tubes being provided with other portions extending across said second flue, and means for causing the steam to flow upwardly through said tubes, and the heated gases 10 to flow downwardly thereover.
6. A steam boiler and its setting comprising a plurality of upper transverse steam and water drums, a lower drum, a flue, a circulatory system between said drums comprising tubes connecting said lower drum to one of said upper steam and water drums located in said flue, a reheater having portions overlapping with said boiler tubes longitudinally of said drums, a second flue adjacent to the 15 first-mentioned flue, other portions of said reheater tubes extending across said second flue, the gases flowing over the overlapping portions of said reheater tubes and then transversely over the remaining portions 20 thereof.
7. In combination, a steam boiler and its setting comprising a first and a second flue, boiler tubes located in said first flue, a reheater comprising tubes extending across and over said second flue into overlapping arrangement with the boiler tubes in said first flue, and other reheater tubes located in and extending across said second flue, the steam flowing through the tubes of said reheater 25 counter to the flow of gases over said reheater.
8. In combination, a steam boiler and its setting comprising a first and a second flue arranged side by side, boiler tubes located in said first flue, a reheater comprising headers, reheater tubes connecting said headers and extending across and over said second flue and in overlapping arrangement with the boiler tubes in said first flue, and other reheater tubes located in and extending across 30 said second flue, the steam flowing through the tubes of said reheater in a direction generally counter to the flow of gases thereover.
9. In combination, a steam boiler and its setting comprising a first and a second flue 35 arranged side by side, boiler tubes located in said first flue, a reheater comprising headers, reheater tubes connecting said headers and extending across and over said second flue and in overlapping arrangement with the boiler tubes in said first flue, and other re-
- heater tubes located in and extending across said second flue, the steam flowing through the tubes of said reheater in a direction generally counter to the flow of gases thereover, the headers for said reheater forming a part 70 of the wall of said second flue remote from said first flue.
10. In combination, a steam boiler and its setting comprising a first and a second flue, boiler tubes arranged in two groups and located on opposite sides of said first flue, a reheater comprising tubes extending across and over said second flue and extending between the said two groups of boiler tubes in overlapping arrangement therewith, and other reheater tubes located in and extending across said second flue, the steam flowing through the tubes of said reheater counter to the flow of gases thereover.
